UNITED STATES PATENT OFFICE.

WILLIAM DANA ORCUTT, OF BROOKLINE, MASSACHUSETTS, ASSIGNOR TO AMERICAN TYPE FOUNDERS COMPANY, OF NEW YORK, N. Y., A CORPORATION OF NEW JERSEY.

DESIGN FOR A FONT OF TYPE.

SPECIFICATION forming part of Design No. 36,729, dated January 5, 1904.

Application filed December 5, 1903. Serial No. 183,984. Term of patent 14 years.

To all whom it may concern:

Be it known that I, WILLIAM DANA ORCUTT, of Brookline, in the county of Norfolk and State of Massachusetts, have invented a new, original, and ornamental Design for a Font of Type, of which the following is a specification.

The design is shown in the accompanying drawings, from which it will be seen that the font comprises capital and small letters, the character "&," together with a set of Arabic numbers.

What I claim as my invention is—
The ornamental design for a font of type as herein shown.

In testimony whereof I hereunto set my name this 19th day of November, 1903.

WILLIAM DANA ORCUTT.
